UNITED STATES PATENT OFFICE.

JOHN MCNEIL AND CHARLES MCNEIL, OF GOVAN, SCOTLAND.

VACUUM-PAN.

SPECIFICATION forming part of Letters Patent No. 664,493, dated December 25, 1900.

Application filed November 8, 1899. Serial No. 736,279. (No model.)

To all whom it may concern:

Be it known that we, JOHN MCNEIL and CHARLES MCNEIL, engineers, subjects of the Queen of Great Britain and Ireland, residing 5 at Govan, in the county of Lanark, Scotland, have invented certain new and useful Improvements in Apparatus for Evaporating or Concentrating Saccharine or other Crystallizable Liquids, of which the following is a specification.

Our said invention comprises certain improvements in the construction and operation of apparatus for evaporating or concentrating saccharine or other crystallizable liquids.

15 Our invention has for its objects the production of a better quality of sugar, a higher yield of crystals, and the reduction of time taken to complete a charge. These objects are attained by having rotating heating-surfaces at 20 different levels and arranging, during the earlier stage of operation, when the liquid forming a charge is being filled in gradually and before crystallization takes place, to mechanically assist the circulation of the liquid 25 by means of a pump. In this way the whole of the heating-surface is continually in use, thereby effecting a saving in time. In the final stage, when the heating-surfaces are fully immersed by the liquid, their rotation directs 30 the path and causes a constant motion of the crystals through the mother-liquid, thus insuring a more regular and uniform crystal, as well as reducing the risk of the formation of false grain.

35 In order that our said invention and the manner of performing the same may be properly understood, we hereunto append three sheets of explanatory drawings, to be hereinafter referred to in describing our improvements.

Figure 1, on Sheet 1 of the drawings, is a side elevation, and Fig. 2, on Sheet 2, a front elevation, of the improved apparatus. Fig. 3, on Sheet 3, is a longitudinal vertical section, and Fig. 4 a transverse vertical section, of a part of the improved apparatus. Fig. 5 is a side elevation, partly in section; and Fig. 6, a transverse vertical section of details in connection therewith.

50 In the drawings the same reference-letters

are used to mark the same or like parts wherever they are repeated.

In carrying out the invention the evaporating vessel A is made with a semicylindrical upper part, with a curved lower part, and with flat vertical ends A', and it is supported on a framing A², fixed to the pillars A³. The requisite heat for the process of evaporation is applied by means of steam admitted to hollow lens-shaped disks B, (shown on Sheet 3,) 55 of which disks there are three sets on three separate hollow shafts C, two upper ones and one lower one. The shafts C are arranged in stuffing-box bearings C', fixed or formed on the end plates A' of the vessel A, to which 60 are externally connected pipes D, with stop-valves D' for admitting steam, similar pipe connections D² for drawing off water of condensation being provided at the other ends of the shafts. The steam on entering each 65 hollow shaft C passes into a compartment D³, Figs. 5 and 6, formed within the shaft, and then enters by ports D⁴ compartments B', formed within each disk by partitions B². The water of condensation passes out of each 70 disk into the hollow shaft by ports D⁵ and is thereafter discharged by a drain-pipe D², fixed to the stuffing-gland. 75

The hollow disks B for each shaft C are formed to fit a key or feather E, Fig. 6, fixed 80 to the shaft, and they are firmly jointed together by nuts E', working on a screwed part of the shaft, the nuts pressing the disks as a whole against a shoulder E², formed on the shaft. The disks are suitably strengthened 85 with internal ribs B³ to prevent any tendency to buckling, while the form of joint between each disk is such as to prevent the slightest liability to leakage. The hollow shafts C are driven by means of spur-wheels C², with one 90 of which there gears a pinion F on a shaft G, having also on it fast and loose pulleys G', driven by a belt G² from a steam-engine H.

The juice or saccharine liquid to be evaporated is supplied to the vessel A by a pipe J, 95 proceeding from a direct-acting steam-pump K, and enters the vessel by two branch pipes J', which cross the vessel and have a number of small tubes J² projecting downward for pouring the liquid over the two upper sets of 100

rotating hollow heating-disks B. The juice forming one charge of the vessel A is filled in gradually, the lower heating-disks B being first partly immersed and then wholly immersed, the juice in rising next gradually immersing the upper two sets of disks B, this mode of working making the evaporating action expeditious. During the first stage of an operation and while the juice or saccharine liquid is being filled in it is made to circulate, and for this purpose the juice is continually withdrawn from the lower part of the vessel A by a pipe L, (which has the supply-pipe L' connected to it at the stop-valve L²,) which is connected to the inlet or suction part of the steam-pump K, the pump forcing the liquid up through the pipes J J' J², so as to descend in a number of small jets upon the hollow rotating heating-disks B. At the same time the liquid is being kept thoroughly mixed by mixers or blades B⁴, fixed to angle-iron bars or frames B⁵, helically fixed to the rotating disks B.

In the final stage and after crystallization has taken place the mechanical circulation of the liquid by means of the pump K is discontinued and the further supply of the liquid for building up the grains is carried on in the usual way.

The circulation and mixing of the liquid in the manner described produces many important and advantageous results, principal among which are that the quantity of first sugars obtainable from a given initial volume of syrup is much increased, the quality of the sugar is also greatly improved, the crystals being more regular, while one of the principal causes of the formation of "false grain" is to a great extent eliminated and also violent ebullition, which causes suspension of liquid particles in the vapor, is prevented. When a charge of the liquid has become sufficiently concentrated, it is emptied from the vessel A through a discharge-valve A⁴, fitted at the bottom of that vessel into a receptacle (not shown) then placed below to receive it.

The top of the vessel A is connected with vacuum-producing apparatus by a large pipe M; but before entering this pipe the vapor passes through appliances for separating particles of liquid carried up in suspension in the vapor. The lower end of the pipe M communicates with a box M', Figs. 3 and 4, occupying a middle part across the space at the upper part of the vessel A, and this box has extending through it and entirely across the vessel A two tubes M², which within the box have openings M³ at their inner sides, while between the box and the end plates of the vessel they have openings M⁴ at their tops. Below the box M' a dished plate M⁵, fixed to snugs M⁶ on the end plates A', extends angularly across the vessel, but with spaces at the

sides for the passage of the vapor, and there are central vertical plates M⁷ in the spaces between the box M' and the end plates. With this arrangement the rising vapor passing the edges of the dished plate M⁵ strikes the plates M⁷ and then finds its way by the tubes M² into the box M', and thence into the ascending pipe M, the effect being, by the baffling of the currents of vapor, to promote the separation from it of suspended particles of liquid. Draining-holes M⁸ are formed in the box M' and the tubes M² to allow the separated particles of liquid collecting in the box and the tubes to fall onto the dished plate M⁵, from which the liquid is drained back again into the vessel over the lower end of the plate, and small draining-holes may also be formed in the plate at suitable parts to further quicken the draining action.

The ascending vapor-pipe M is connected to a jet-condenser N, supplied with cold water by a pipe N' and connected by a pipe N² to an air-pump P. From the bottom of the condenser N a pipe N³ for the discharge of water descends sufficiently far down to form a Torricellian vacuum-column. The water, as well as the air, might, however, be withdrawn from the condenser by means of pumps.

The discharge-pipe P' of the air-pump P is by branch pipes P² and stop-valves P³ connected to the suction-pipe N², so that the pump may be made to pump air through the condenser N and pipe M into the vessel A in order to apply pressure in that vessel when discharging a charge of concentrated juice or liquid from it, a valve N⁴ on the pipe N³ being then closed.

Pressure-gages Q, safety-valves R, and other appliances are provided, as is usual with apparatus for evaporating or concentrating juices or saccharine liquids.

What we claim as our invention is—

1. In apparatus for evaporating or concentrating saccharine or other crystallizable liquids, a series of hollow lens-shaped disks, fixed upon a hollow shaft, with means for admitting steam thereto and withdrawing water of condensation therefrom, in combination with an inclosing casing for the whole, a vacuum-producing apparatus connected with said casing and baffling means at the top of the casing, comprising a box, tubes passing through the box and extending out from it across the casing and having ports or openings, a curved plate under the box, and vertical plates at the sides thereof, all substantially as described.

2. In apparatus for evaporating or concentrating saccharine or other crystallizable liquids, the combination in one vessel of two or more heaters, each comprising a series of hollow lens-shaped disks, a hollow shaft carrying the same, means for admitting steam thereto and withdrawing water of condensation therefrom, in combination with an in-

closing casing for the whole, means at the top of the casing for baffling the rising vapors and a vacuum-producing apparatus, connected to the casing, substantially as described.

5 3. In apparatus for evaporating or concentrating saccharine or other crystallizable liquids, the combination of an inclosing casing with a hollow shaft, a series of hollow lens-shaped heating-disks on said shaft, frames 10 helically fixed to the series of disks and blades

carried by said frames, all substantially as described.

In testimony whereof we have signed our names to this specification in the presence of two subscribing witnesses.
